(57) **CLAIM**

We claim the ornamental design for a patch with electrode array, as shown and described.

DESCRIPTION

FIG. 1 is a top perspective view of an patch with electrode array showing our new design;

FIG. 2 is a bottom perspective view thereof;

FIG. 3 is a top view thereof;

FIG. 4 is a bottom view thereof;

FIG. 5 is a side view thereof;

FIG. 6 is a side view thereof;

FIG. 7 is a side view that opposes the side view of FIG. 6; and,

FIG. 8 is a side view that opposes the side view of FIG. 5. The broken lines are included for purpose of illustrating portions of the patch with electrode array that form no part of the claimed design.
